UNITED STATES PATENT OFFICE.

JOHN A. STONE, OF CHICAGO, ILLINOIS, ASSIGNOR TO INTERNATIONAL HARVESTER COMPANY OF NEW JERSEY, A CORPORATION OF NEW JERSEY.

CORN-HUSKER.

1,226,718.

Specification of Letters Patent. Patented May 22, 1917.

Application filed March 9, 1914. Serial No. 823,620.

To all whom it may concern:

Be it known that I, JOHN A. STONE, a citizen of the United States, residing at Chicago, in the county of Cook and State 5 of Illinois, have invented certain new and useful Improvements in Corn-Huskers, of which the following is a full, clear, and exact specification.

My invention relates to corn huskers, and 10 in particular to an improved form of coacting husking rolls operative to remove the husks from the ears as they become engaged thereby.

The object of the invention is to provide 15 a form of coacting husking rolls that may be sufficiently aggressive in their function to remove the husks from the ears of corn without engaging with the kernels to remove them from the cob and thus causing a result- 20 ant waste of corn that has been found to be more or less prevalent heretofore in the operation of the class of machines indicated. These objects are attained by means of mechanism, one embodiment of which is 25 illustrated in the accompanying drawing, in which—

Figure 1 is a top plan view of a pair of coacting husking rolls, broken away at their middle and embodying my invention;

Fig. 2 is an end elevation of Fig. 1; and Fig. 3 is an enlarged cross section of the rolls along line 3—3 of Fig. 1 looking in the direction of the arrow.

Referring to the drawings, wherein the 35 same reference characters designate like parts throughout the several views 1 and 2 represent cylindrical shafts having husking rolls 3 and 4, respectively, secured thereon, the shafts being driven in opposite direc- 40 tions by any desired means. The rolls are provided with collar portions 5 at their opposite ends that engage with each other in a manner preventing the operative portions of the rolls from contacting with each other 45 in the operation of the machine. The bodies of the opposing rolls are provided with diametrically opposed and longitudinally disposed ribs 6, parallel and concentric with their axes, the intervening space between the 50 ribs being cylindrical in form and concentric with the axis of the roll, and 7 represents oppositely disposed spirally arranged ribs in parallel relation, leading rearward in the direction of rotation of the rolls and 55 having their opposite ends terminating be-

low the periphery of the parallel ribs 6. The spirally arranged ribs 7 form between them depressed concentric, spiral channels 8 parallel thereto and are each provided with a series of angular or peaked teeth 9 upon their peripheries that extend transversely thereof approximately half way to the bottom of the channels. One of the co-acting rolls, as 4, is provided with a series of spaced sockets 10 disposed radially in front of the ribs 6 adjacent thereto, and in the direction of rotation of the roll and parallel therewith, the sockets receiving plugs 11 in which are driven husking pegs 12 that curve forward beyond the periphery of the roll and are received by the channels 8 of the opposing roll.

In operation the rolls are given a rotative movement in opposite directions, as shown by the arrows in Fig. 3, the teeth 9 and the 75 husking pegs 12 loosening the husks so that they are engaged by the peripheries of the longitudinal ribs 6 and removed from the ears.

Although I have herein specifically described one embodiment of my invention, it is to be understood that the form shown is chosen for purposes of illustration and that my invention may be embodied in various other forms without departing from its 85 spirit.

What I claim as my invention and desire to secure by Letters Patent is:

1. A husking roll having spaced longitudinally extending rib members thereon, 90 and a plurality of series of parallel spirally arranged toothed rib members between said longitudinally extending rib members, the longitudinally extending rib members projecting above said spiral rib members 95 whereby the former may exert a positive thrust upon an ear of corn at definite intervals.

2. A pair of coacting corn husking rolls rotatable in opposite directions having continuous longitudinally arranged coacting parallel rib members forming a part of each roll, and coöperating oppositely disposed spirally arranged ribs between and in contact with said parallel rib members on 105 each of said rolls.

3. A pair of coacting corn husking rolls rotatable in opposite directions having longitudinally arranged coacting parallel rib members forming part of each roll, and op- 110

positely disposed spirally arranged rib members on each of said rolls leading rearward in the direction of rotation of the rolls and provided with husk engaging teeth upon their peripheries.

4. A pair of coacting corn husking rolls rotatable in opposite directions having longitudinally arranged coacting parallel rib members forming part of each roll, and oppositely disposed spirally arranged rib members on said rolls leading rearward in the direction of rotation of the rolls and having husk engaging teeth upon their edges, the spirally arranged ribs being of less radii than those arranged longitudinally.

5. A pair of coacting corn husking rolls rotatable in opposite directions having longitudinally arranged coacting parallel rib members forming part of each roll, oppositely disposed spirally arranged rib members leading rearward in the direction of rotation of the rolls and having husk engaging teeth upon their peripheries, the spirally arranged ribs being of less radii than those arranged longitudinally, and spaced husk engaging pegs disposed between the longitudinal ribs upon one of the rolls and extending beyond their peripheries into the channels between the spirally arranged ribs upon the opposing roll.

6. A pair of coacting corn husking rolls rotatable in opposite directions having longitudinally arranged coacting parallel rib members forming part of each roll, oppo-

sitely disposed spirally arranged rib members leading rearward in the direction of rotation of the rolls and having husk engaging teeth upon their peripheries, the spirally arranged ribs being of less radii than those arranged longitudinally, and spaced husk engaging pegs disposed between the longitudinal ribs upon one of said rolls in a parallel line therewith and extending beyond their peripheries into the channels between the spirally arranged ribs upon the opposing roll.

7. A pair of coacting corn husking rolls rotatable in opposite directions having longitudinally arranged coacting parallel rib members forming part of each roll, oppositely disposed spirally arranged rib members leading rearward in the direction of rotation of the rolls and having husk engaging teeth upon their peripheries, the spirally arranged ribs being of less radii than those arranged longitudinally, and spaced husk engaging pegs disposed adjacent the front side of one of said ribs in the direction of rotation of the roll in a line parallel therewith and extending beyond their peripheries into the channels between the spirally arranged ribs upon the opposing roll.

In testimony whereof I affix my signature, in the presence of two witnesses.

JOHN A. STONE.
